(57) **CLAIM**

The ornamental design for a fairing, as shown and described.

DESCRIPTION

FIG. 1 is a top, front, left side perspective view of the first embodiment of a fairing of the present design;

FIG. 2 is a top view thereof;

FIG. 3 is a bottom view thereof;

FIG. 4 is a front view thereof;

FIG. 5 is a rear view thereof;

FIG. 6 is a left side view thereof, with the right side view being a mirror image thereof;

FIG. 7 is a top, front, left side perspective view of the fairing of the present design, shown mounted on an unclaimed truck, in condition of use;

FIG. 8 is a top, front, left side perspective view of the fairing of the present design, shown on an unclaimed truck with trailer, in condition of use;

FIG. 9 is a top, front, left side perspective view of the second embodiment of the fairing of the present design;

FIG. 10 is a top view of the second embodiment thereof;

FIG. 11 is a bottom view of the second embodiment thereof;

FIG. 12 is a front view of the second embodiment thereof;

FIG. 13 is a rear view of the second embodiment thereof; FIG. 14 is a left side view of the second embodiment, with the right side view being a mirror image thereof;

FIG. 15 is a top, front, left side perspective view of the second embodiment of the fairing, shown mounted on an unclaimed truck, in condition of use;

FIG. 16 is a top, front, left side perspective view of the third embodiment of the fairing of the present design;

FIG. 17 is a top view of the third embodiment thereof;

FIG. 18 is a bottom view of the third embodiment thereof;

FIG. 19 is a front view of the third embodiment thereof;

FIG. 20 is a rear view of the third embodiment thereof;

FIG. 21 is a left side view of the third embodiment, with the right side view being a mirror image thereof; and,

FIG. 22 is a top, front, left side perspective view of the third embodiment of the fairing, shown mounted on an unclaimed truck, in condition of use.

The broken lines illustrating a truck and trailer represent environment structure that forms no part of the claimed design. The remaining broken lines illustrate portions of the fairing that forms no part of the claimed design.
